UNITED STATES PATENT OFFICE.

AINER W. JUNTUNEN, OF ROLLA, NORTH DAKOTA.

PRIMING APPARATUS FOR INTERNAL-COMBUSTION ENGINES.

1,108,760.

Specification of Letters Patent. Patented Aug. 25, 1914.

Application filed February 7, 1914. Serial No. 817,304.

To all whom it may concern:

Be it known that I, AINER W. JUNTUNEN, a citizen of the United States, residing at Rolla, in the county of Rolette and State of North Dakota, have invented new and useful Improvements in Priming Apparatus for Internal-Combustion Engines, of which the following is a specification.

This invention relates to priming apparatus for internal combustion engines, the object in view being to provide simple expeditiously operable apparatus of the character referred to which may be manipulated successfully without lifting the hood 15 which covers the engine and without the operator leaving his seat in the machine.

A further object of the invention is to provide apparatus of the character referred to which embodies such simple and economical 20 construction that it may be manufactured and sold at small cost and readily applied to any multiple cylinder internal combustion engine.

With the above and other objects in view, 25 the invention consists in the novel construction, combination and arrangement of parts, as will hereinafter be more fully described, illustrated and claimed.

In the accompanying drawings:—Figure 30 1 is a side elevation partly in section conventionally showing a multiple cylinder internal combustion engine with the priming apparatus of this invention applied thereto. Fig. 2 is an enlarged sectional view through 35 one of the priming valves and the parts adjacent thereto showing the valve in its normal closed position. Fig. 3 is a similar view showing the position the valve assumes when in readiness to receive fuel and relieve 40 compression. Fig. 4 is a similar section showing the position the valve assumes in priming the cylinder. Fig. 5 is a detail elevation showing the operating handle or lever and the sector with which it coöperates.

45 Referring to the drawings A designates generally a multiple cylinder internal combustion engine which is conventionally shown as comprising the cylinders B, C designating the dash of an automobile and D 50 the fuel supply which, if desired, may consist of the ordinary fuel tank under the front seat of the machine or in any other location desired.

In carrying out this invention, a fuel feed 55 pipe 1 extends from the fuel supply tank D along the top of the several cylinders B

where it is provided with branches 2 leading to a series of valve casings 3 in which the priming valves are arranged. In connection with the cylinders I employ a series of 60 valves 4 having their longitudinal axes arranged in a common plane as indicated in Fig. 1, each of said valves being provided at its opposite ends with longitudinally extending stems one of which, in the preferred 65 embodiment of this invention, is terminally slotted as shown at 5 to receive the adjacent end of the stem at the opposite end of said valve, the stems of two adjoining valves being connected for simultaneous rotation by 70 means of a pin 6 shown in the form of a split cotter pin for convenience and to facilitate the ready assembling of the parts of the priming apparatus. Each valve 4 is provided in one face thereof with a fuel 75 cavity or pocket 7 adapted to contain a suitable amount of liquid fuel for priming the respective cylinder. In addition to the cavity 7 the valve is further provided with a compression relief passage 8 which extends 80 transversely through the same at an oblique angle, one end of the passage being arranged in transverse alignment with one end of the cavity 7 so that both the cavity 7 and the passage 8 may be placed in communication 85 with the pipe or nipple 9 which leads from the valve casing 3 into the adjacent cylinder. The opposite end of the passage 8 is adapted under one position of the valve 4 to register with a vent 10 in the valve casing 3 so as 90 to permit any compressed air or gas to escape from the cylinder immediately associated therewith. The valve casing 3 is also provided with a gas inlet port 11 to which one of the branches 2 of the feed pipe 1 is 95 connected. The stem of the valve nearest the dash C is extended through an opening 12 in the dash as shown and is provided with an operating handle or lever 13 which is movable across a segment 14 secured for convenience to the dash C and provided with three notches 15, 16 and 17 into which the operating handle or lever 13 is adapted to snap so as to hold said lever fixed.

In order to prime the cylinders, the operating handle or lever 13 is moved from the intermediate position shown in Figs. 1 and 5 to one of the notches 15 or 17 so as to bring the cavity 7 uppermost to receive a charge of fuel and under this adjustment of the 110 valve, the relief passage 8 registers with the priming inlet of the cylinder and also

the vent 10 of the valve casing. This releases any compressed gas in the cylinders. The operating handle or lever 13 is then turned to the extreme limit of its movement 5 in the opposite direction which imparts a half turn to the valve 4 and brings the charging cavity 7 into communication with the priming inlet connection 9 of the cylinder, the priming liquid flowing then into 10 the combustion chamber of the cylinder. The operating handle or lever 13 is then restored to its middle position whereupon the valve is closed and the cylinders are all 15 primed and ready for ignition. The engine may then be started by any of the usual methods.

It will be observed that the priming of the cylinders takes place without the necessity of lifting the hood which covers the 20 engine and also without the necessity of the operator dismounting from his seat in the machine. He may successively prime the cylinders of the engine as frequently and

rapidly as may be necessary in getting the engine started.

What I claim is:—

Priming apparatus for multiple cylinder internal combustion engines comprising a series of axially aligned priming valves, longitudinally aligned stems for said valves connected to each other for simultaneous turning movement, valve casings for said valves attached to and communicating with the respective cylinders, a feed pipe leading from the fuel supply to said valve casings, and means for turning said valves, each of said valves embodying a fuel cavity in one side and a compression relief passage adapted to register with the priming inlet of its cylinder under different positions of said valve.

In testimony whereof I affix my signature in presence of two witnesses.

AINER W. JUNTUNEN.
